SPEED-CHANGING APPARATUS

Frank Breckenridge, Teaneck, N. J., assignor to
Westinghouse Electric Corporation, East Pittsburgh, Pa., a corporation of Pennsylvania

Application June 15, 1946, Serial No. 677,030

4 Claims. (Cl. 74—291)

1

This application is a continuation-in-part of the copending application filed jointly by Hilbert E. Edwards and myself for improvement in Cleaning apparatus, Serial No. 476,838, and filed February 23, 1943.

My invention relates to speed-changing apparatus and has for an object to provide improved apparatus of this kind.

A still further object of the invention is to provide improved speed-changing apparatus for a cleaning and centrifuging machine which apparatus is relatively light in weight and inexpensive to construct.

It is a still further object of the invention to prevent the escape of lubricant from an oil-containing speed-change mechanism of a laundry machine operating at different speeds for the washing and centrifuging of fabrics.

These and other objects are effected by my invention as will be apparent from the following description and claims taken in connection with the accompanying drawings, forming a part of this application, in which:

Fig. 1 is a vertical elevation of a portion of a laundry machine having applied thereto, a speed-changing mechanism constructed in accordance with my invention; portions of the machine being shown in section for clearness;

Fig. 2 is a section taken along the line II—II of Fig. 1;

Fig. 3 is a sectional view of my improved speed changing mechanism, and is taken along the line III—III of Fig. 5; and

Figs. 4 and 5 are, respectively, sections taken along the lines IV—IV and V—V of Fig. 3.

Reference will now be had to the drawings wherein I have shown my invention applied to a washing and spinning machine of the type shown in the patent to Frank Breckenridge et al. No. 2,296,261, dated September 22, 1942, and assigned to the assignee of the present application. This type of machine includes a tub structure enclosing a basket rotatable at different speeds for washing and centrifuging the fabrics about an axis inclined at an acute angle from the vertical. A portion of the tub is shown at 10 and includes a side wall 11 and an end wall 12, the side wall 11 having a drain opening 13 formed therein. The basket is shown generally at 14 and includes a side wall 15 having a plurality of inwardly-extending vanes formed therein, one of the vanes being shown at 16. The side wall 15 of the basket is perforate throughout, substantially, its extent, a portion of the perforations being shown at 17. The lower end wall of the basket, shown at 18,

2

extends inwardly of the basket to define a dome. The basket is carried by a stub shaft 19 which is rotatable about an oblique axis.

5 A plurality of axially-spaced, anti-friction bearings 21 support the stub shaft 19, which bearings 21 are carried by a bearing sleeve 22 secured at one end to the end wall of the tub 12. A bracing wall 23 is fixed to the sleeve 22 adjacent its other end and the outer portion of the bracing wall 23 is welded or otherwise secured to the tub 12, as shown at 24.

Rotation of the stub shaft 19 at a relatively low speed for washing and at a relatively high speed for centrifuging fluid from the fabrics is effected by a motor 25 and a two-speed mechanism, generally shown at 26 and constructed in accordance with my invention. The motor 25 is supported from the tub structure 10 by a bracket construction including a bracket 27 welded or otherwise secured at its upper end to the wall member 23 of the tub 10. One end of the motor 25 is carried by the lower end of the bracket 27, suitable clamps 28 being provided for clamping the motor to the bracket 27. The opposite or 20 forward end of the motor 25 may also be supported by a bracket (not shown) carried by the tub 10.

25 The two-speed mechanism shown at 26 includes respective driven and driving shafts 31 and 32 which are concentrically arranged and rotatable about an oblique axis substantially parallel to the axis of the stub shaft 19. The driven shaft 31 carries a pulley 33 which is connected by means of a belt 34 to a pulley 35 rotated by the motor 25. The driving shaft 32 carries a pulley 36 connected by means of a belt 37 to a sheave 38 secured to one end of the stub shaft 19. An axially-extending flange 39 is provided on the pulley 33 for a purpose to be referred to hereinafter.

30 The two-speed mechanism 26 includes an enclosing casing 40, the front end of which is provided with a plurality of supporting ears 41, each of which is provided with an opening for the reception of supporting rods 42. The rods 42 are 35 carried by a flange 43 forming a part of the bracket member 27. Preferably, the rods are secured to the flange 43 by nuts 44. A pair of springs 45 carried by the respective rods 42 engage the ears 41 and bias the multiple-speed 40 mechanism 26 downwardly and to the right, as viewed in Fig. 2, whereby the belts 34 and 37 are tensioned.

45 Reference will now be had to Figs. 3, 4 and 5, showing the construction of the two-speed mechanism 26 in detail. This mechanism is of the 50

planetary gear type and includes a sun gear 46 which is preferably cut in the shaft 31, a plurality of planet gears 47, and an orbit gear 48 formed interiorly of an orbit gear structure 49. The planet gears 47 are carried by axles 51 which are fixed to a spider 52 carried by and rotatable with the hollow driving shaft 32. The driving shaft 32 is provided interiorly, with bearings 53 which rotatably support one end of the driven shaft 31. Support for the driving shaft 32 is provided by a bearing 54 carried by an end wall 55 of the casing structure 40. The opposite or rear end of the driven shaft 31 is journaled in a suitable bearing 56 supported by an opposite end wall 57 of the casing 40.

The orbit gear structure 49 is carried by the spider 52 by means of a bushing 58 so that the spider 52 and the orbit gear structure 49 may rotate relative one another. As described hereinafter, the spider 52 may be moved slightly in an axial direction. Accordingly, the connecting bushing 58 is so constructed that the orbit gear structure 49 will move axially with the spider 52. This operation may be accomplished by providing the bushing 58 with a shoulder 59 engaging the end of the orbit gear structure 49.

An axial thrust is imparted to the spider 52 and the orbit gear structure 49 to the right (as shown in Fig. 3) by a spring structure 61, one end 62 of which bears against the end wall 55 and the inner end 63 of which bears against the spider 52 and the bushing 58. During low-speed operation of the mechanism the spring 61 forces an end 64 of the orbit gear structure 49 into engagement with an annular shoulder 65 formed on the casing 40. As described hereinafter, the end portion 64 and the annular shoulder 65 define a brake for the orbit gear structure 49 when the mechanism is actuated to its low-speed position after having been operated at high speed.

A clutching mechanism, generally shown at 66, is interposed between the driven shaft 31 and the spider 52 for locking these members together during high-speed operation. The clutch 66 may be of any suitable construction, but preferably is of the disc or plate type, and includes a plurality of discs 67 which are carried by a clutch plate 68 and rotatable therewith. The clutch plate 68 is provided with a plurality of inwardly-extending teeth 69 which intervene between the ends of the teeth of the sun gear 46 so that the clutch plate 68 rotates at all times with the sun gear 46 and the driven shaft 31. A shoulder 71 is provided on the driven shaft 31, which engages the ends of the inwardly-extending teeth 69 so that the clutch plate 68 will move axially with the shaft 31, as described hereinafter. The rotatable clutch discs 67 intervene between and are engageable with a plurality of discs 72 rotatably adjacent their outer peripheries, by a holder 73, the latter being secured to the spider 52. Preferably, the spider includes a plurality of outwardly-extending arms 74 which are riveted, as shown at 75, to the holder 73 (see Figs. 3 and 5).

Engagement and disengagement of the clutch 66 are effected by imparting slight axial movements to the shaft 31. As shown in the drawing, the clutch 66 is disengaged so that the mechanism operates to rotate the driving shaft 32 at low speed. In this position of the apparatus the surface 64 of the orbit gear structure 49 frictionally engages the annular shoulder 65 of the casing so that the orbit gear structure is stationary. Accordingly, the spider 52 is driven by the planet gears 47 as they are rotated within the

orbit gear 48. As the spider is fixed to the driving shaft 32, the pulley 36 is rotated at a speed lower than the speed of the pulley 33.

High-speed rotation of the driven pulley 36 is effected by imparting a slight axial movement to the shaft 31 to the left as viewed in Fig. 3. This movement causes the shoulder 71 to engage the inward teeth 69 of the clutch plate 68, whereby the clutch plate 68 is moved to the left and compresses the discs 67 and 72. Accordingly, the clutch 66 is engaged and the spider 52 is locked to the driven shaft 31 so that both pulleys 33 and 36 and their respective shafts operate at the same speed. The axial movement imparted to the shaft 31 and clutch plate 68 moves the spider 52 slightly to the left in opposition to the bias of the spring 61 whereupon the orbit gear structure 49 is relieved of the bias of the spring and the braking effect provided by its surface 64 and the shoulder 65 is terminated. In this high-speed position, it will be apparent that planet gears 47, the sun gear 46, and the orbit gear 49 are locked together so that they rotate as a unit.

The means for moving the shaft 31 axially includes a solenoid 75 having a movable armature 76 connected to a crank arm 77 which is pivoted by a tongue and slot connection to a bracket 78 carried by the casing end wall 57. The arm 77 carries a push button 79 which engages a small plate 81 carried on the exterior of a flexible wall or bellows 82. The inner surface of the bellows 82 carries a block 83 which is in engagement with a ball 84 carried in a recess formed in the end 35 of the driven shaft 31. The bellows 82 is secured to a cup 85 formed on the casing end wall 57 and defines a fluidtight seal between the interior and exterior of the casing 40. Accordingly, escape of lubricant at this point is precluded.

During periods when the solenoid 75 is deenergized, the apparatus occupies the position shown in Fig. 3, wherein the shaft 31 is in its right-hand axial position with the clutch 66 disengaged. Upon energization of the solenoid 75, the armature 76 and the crank arm 77 move to the left and slightly compress the bellows 82, whereupon the shaft 31 is moved axially to the left. This movement engages the clutch 66 and effects high-speed operation of the apparatus as described.

When the two-speed mechanism 26 is applied to a washer of the type shown in Fig. 1, the shaft 31 is oblique so that the wall 57 of the casing 40 is lowermost. Accordingly, the shafts 31 and 32 project through the upper end wall 55 of the casing and in this oblique position, the escape of lubricant from the casing 40 is prevented. Any tendency for the lubricant to escape along the shafts 31 and 32 is counteracted by gravity. By terminating the driven shaft 31 inwardly of the flexible wall 82, the escape of oil from the lower end of the casing is impossible, it being understood that the flexible wall 82 is connected in fluid-tight relationship with the casing 40.

During low-speed operation of the mechanism, the spider 52 and the planet gears 47 rotate in clockwise direction as viewed in Fig. 5. At this time, there is, of course, a tendency for the orbit gear structure 49 to rotate in counterclockwise direction. This tendency is, of course, resisted by the frictional engagement of the surface 64 on the shoulder 65. In order to positively prevent any counterclockwise rotation of the orbit gear structure 49, a pawl and ratchet mechanism shown in Fig. 4 is provided. This mechanism includes a plurality of ratchet teeth 86 formed on

the orbit gear structure 49 and engageable with a pawl 87 pivoted at 88 to the casing 40. In order to prevent noise caused by the pawl 87 riding upon the teeth 86 during high-speed operation, or when the orbit gear structure 49 is rotated clockwise, a resilient drag ring 89 is provided. This ring 89 frictionally engages an undercut portion 91 formed in the ratchet teeth 86 and, therefore, tends to rotate at all times with the orbit gear structure 49. Upon slight clockwise movement of the orbit gear structure 49, as viewed in Fig. 4, an upwardly-extending end 90 of the drag ring 89 engages the surface 92 defined by a slot in the pawl 87 and moves the pawl upwardly out of engagement with the teeth 86. When the mechanism is adjusted for slow-speed operation, the pawl 87 is retained out of engagement with the teeth 86 until rotation of the orbit gear structure is terminated and slight counterclockwise movement imparted thereto by the planet gears 47. As the orbit gear structure 49 moves slightly counterclockwise, the end 91 of the drag ring 89 engages the surface 93 of the pawl and swings the pawl downwardly into operative engagement with the ratchet teeth 86, whereupon further clockwise movement of the orbit gear structure 49 is prevented.

Washing apparatus of the type disclosed herein usually employs a pump for removing vitiated water discharged through the drain opening 13 and for removing the water thrown from the clothes during centrifuging. The pump for this purpose is shown at 95, the inlet of which is connected by a flexible conduit 96 to a sump 97 communicating with the discharge opening 13. The outlet opening 98 of the pump is connected by a flexible conduit, not shown, to a point of discharge. The pump 95 may be of the well-known centrifugal type and includes a rotating driving shaft 99 having a wheel 101 keyed or otherwise fixed thereto for driving the same. As best shown in Fig. 1, the wheel 101 is arranged within the annular flange 39 of the pulley 33 and during operating periods of the pump 95, the wheel 101 is held in frictional engagement with the flange 39. When the pump 95 is to be stopped, the wheel 101 is moved upwardly out of engagement with the flange 39. This operation is accomplished, as best shown in Figs. 1 and 2, by pivotally supporting the pump 95 by means of a suitable pivot 102 to the bracket 21. The pump structure is biased upwardly toward its inactive position by a spring 103 interposed between a plate 104 carried by the pump structure 95 and the second plate 105 forming a part of the bracket 21. Movement of the pump structure 95 to its active position is effected by a solenoid 106, the armature 107 of which is connected by a spring 108 to an arm 109 forming a part of the pump structure 95.

It will be apparent from the foregoing description that I have provided an improved speed-reducing and speed-changing mechanism for a washing and spinning machine wherein loss of lubricant from the mechanism is prevented. I make no claim to the combination of the speed-changing mechanism and the driving and driven elements of the washing machine disclosed but I do claim as new a speed-changing mechanism per se having adjusting means cooperating with the flexible wall member 82, the latter precluding the loss of lubricant from the casing of the speed-changing mechanism.

While I have shown my invention in but one form, it will be obvious to those skilled in the art

that it is not so limited, but is susceptible of various changes and modifications without departing from the spirit thereof.

What I claim is:

- 5 1. In speed-changing apparatus, the combination of a casing including first and second end walls, a variable speed mechanism arranged within the casing, driving and driven shafts connected to said mechanism and extending through 10 said first end wall of said casing, said second end wall of the casing having a portion thereof of flexible construction, and means for varying the speed of said variable speed mechanism including an adjustable movable member arranged exteriorly of the casing and engaging said end wall portion of flexible construction.
- 15 2. In speed-changing apparatus, the combination of a casing including upper and lower end walls, a variable speed mechanism arranged within the casing, driving and driven shafts connected to said mechanism and extending through said upper end wall of the casing, said driving and driven shafts having their axes of rotation inclined at an acute angle from the horizontal, 20 25 said lower end wall of the casing having a portion thereof of flexible construction, and means for varying the speed of said variable speed mechanism including an adjustable member arranged exteriorly of the casing and engaging said end wall portion of flexible construction.
- 30 3. In speed-changing apparatus, the combination of a casing having upper and lower end walls, a variable speed mechanism arranged within the casing, driving and driven shafts connected to said mechanism and extending through said upper end wall of the casing, said shafts having their axes of rotation inclined from the horizontal, 35 said lower end wall of the casing having a portion thereof of flexible construction, and means for varying the speed of said variable speed mechanism including a member arranged within the casing and engaging the inner surface of the end wall of flexible construction and an adjustable member disposed exteriorly of the 40 casing and engaging the outer surface of said end wall portion of flexible construction.
- 45 4. In speed-changing apparatus, the combination of a casing structure having upper and lower end walls, a variable speed mechanism arranged 50 within the casing, driving and driven shafts concentrically arranged and connected to said mechanism, said shafts being rotatable about an oblique axis and said shafts extending through said upper end wall of the casing, said lower end 55 wall of the casing including a portion of flexible construction, and means for varying the speed of said variable speed mechanism including a member arranged exteriorly of the casing and engaging the end wall portion of flexible construction.
- 60
